METAL KEG

Filed Sept. 20, 1922

2 Sheets-Sheet 2

UNITED STATES PATENT OFFICE.

RALPH E. BLACKFORD, OF MIDDLETOWN, OHIO.

METAL KEG.

Application filed September 20, 1922. Serial No. 539,291.

To all whom it may concern:

Be it known that I, RALPH E. BLACKFORD, a citizen of the United States, residing in Middletown, in the county of Butler and State of Ohio, have invented certain new and useful Improvements in Metal Kegs or the like, of which the following is a specification, reference being had therein to the accompanying drawings.

This invention relates to improvements in metal kegs, or the like, having particular reference to kegs of the knock-down type.

An object of the invention is to provide a metal keg having its parts designed for cheap production, and suitable for shipping knocked-down to minimize the bulk of the cargo and the cost of shipment, the invention, as here shown, being an improvement of the construction shown in my copending application for Letters Patent, Serial No. 538,679, filed February 23, 1922.

The main object of the present invention is to provide an improved head construction whereby the keg will be made stronger and better adapted for heavy materials, as nails, nuts, washers, bolts, screws, etc., in connection with which the kegs receive very hard usage.

A further object of the invention is to provide an improved head construction consisting of but one piece which is adapted to interlock with the end of the keg in a positive and very substantial manner, the assembly of the parts being readily made, the heads at both ends of the keg being sunk, or set inwardly of the ends, sufficiently to provide an adequate flange for gripping the keg in handling.

Finally, it is an object of the invention to provide an improved metal keg which will be durable, and in all respects suitable for its intended purposes.

In the accompanying drawings:

Fig. 1 is a side elevation illustrating a metal keg of the improved construction.

Fig. 2 is an end view of the keg, the head being removed.

Fig. 3 consists of end and side views respectively, of an interlocking lug used in connection with the bands or hoops.

Fig. 4 is a detail view of the keg in longitudinal section.

As here shown, the parts of the keg con-

sist of the body portion —1, heads —2, interlocking bands —3, and intermediate band —4, all the parts being designed for knock-down construction.

The body —1 consists of an integral piece of sheet metal having its opposite edges of the shortest dimension shaped to form joint —5 when the edges are brought together to form the cylindrical body of the keg,—the outward spring of the metal, when the edges are engaged one with the other, acting to hold the same together to permit of slipping the band —4 over the end of the keg and bringing the same to position intermediate the ends as shown in Fig. 1.

Before part —1 is formed into the cylindrical shape, a series of channels —6 are formed in the metal to extend longitudinally of the body of the keg when the same is assembled,—the channels being formed inwardly and open as at —7 to the periphery of the body —1,—the bottom —8 of the channels being substantially flat, and wider than the opening —7, thus causing the opposite sides —9 to be inclined as best shown in Fig. 2. The channels are tapered longitudinally, increasing in width gradually from the middle portion of the keg outwardly. Adjacent its opposite ends the keg has external annular grooves —10 formed therein to receive the interlocking bands —3 and intersecting the grooves a series of apertures or slots —11 formed therein which serve to receive outwardly projected bands or loops —12 formed integrally with the heads —2 and through which the interlocking bands —3 pass,—the ends of the bands, here shown as a wire, being twisted together as at —13 to firmly interlock the heads with the ends of the keg.

The heads —2 of the keg are interchangeable one with the other, and consist of circular pieces of metal adapted to be produced as punchings. The heads rest, as the keg is assembled, over the ends of the channels —6,—the walls of the channels being cut away at their ends as shown in Fig. 4 to permit the heads of the keg to be properly seated in the ends, the loops —12 being pressed outwardly through apertures —11 in any suitable manner after the heads have been seated on the body of the keg.

As shown in Fig. 4, the rims —14 of the

heads are rolled outwardly to form a smooth edge and also to form the seat for the heads to rest on the ends of the keg as shown at —15, the ends of the keg being flared outwardly somewhat as indicated at —15^a. The heads as shown are pan-shaped or sunk inwardly to form relatively wide flanges —16 which serve to protect the bottoms —17 and as a means for gripping the ends of the keg 10 for handling the same.

The joint —5 is of an improved construction over that shown in my copending application referred to, the present construction being simpler and easier to assemble. As 15 here shown, the joint is made by forming a compound flange —18 upon one of the coacting edges, and a single flange —19 upon the other edge, the juncture being then made, as illustrated in Fig. 2, by entering the single 20 flange in the double, the outward spring of the metal acting to hold the edges together as the band —4 is assembled on the keg.

The interlocking lugs —20, illustrated in detail in Fig. 3, are a further improvement 25 over the construction shown in my copending application herein referred to, the present construction being simpler to make, and adapted to effect a firmer interlocking relation between the band —4 and the channels

30 —6. As here shown, the lugs are rectangularly shaped and open at one side as at —21, which adapts the lugs to be clamped over band —4 as indicated at —22 in Fig. 1, the band being stiffened by a bead —4^a and having notches —23 formed in the opposite edges thereof in register with each of the channels —6 to prevent relative movement between the lugs and band. The opposite sides of the lugs are angular shaped as indicated at —24, thus to form a dove-tail 35 interlocking relation with channels —6 which serves to hold bands —4 in firm frictional engagement with the body of the keg, but adapted to be readily disengaged therefrom to disassemble the parts.

From the foregoing detailed description the improved construction set forth herein will be readily understood.

Having described my invention, I claim:

50 1. In metal kegs, including in combination with the body and heads of the keg, a plurality of channels extended parallel one with another longitudinally of said body and open outwardly to the periphery thereof, and an intermediate band having a series of lugs assembled thereon and adapted to register with and to effect interlocking relations with said channels as said ring is brought to position on said body.

60 2. In metal kegs, including in combination with the body and heads of the keg, a plurality of channels, angular-shaped in cross section, and extended longitudinally of said body and open outwardly to the periphery thereof, and an intermediate band

having off-set lugs assembled thereon and adapted to register with and to effect dove-tailed interlocking relations with said channels as said ring is brought to position on said body.

70 3. In metal kegs, including in combination with the body of the keg, a series of apertures arranged circumferentially of said body adjacent an end thereof, an external, circumferentially arranged groove connecting said apertures, a head for the keg having a portion extended into said end, said portion having a series of outwardly extended loops formed therein and adapted to register with and project through said apertures, and an annular band extended in said groove, and through said loops acting to interlock the head of the keg with said body.

75 4. In metal kegs, including in combination with the body of the keg, a series of apertures arranged circumferentially of said body adjacent an end thereof, a head for the keg having a portion extended into said end, said portion having a series of outwardly extended loops formed therein and adapted to register with and project through said apertures, and an annular band passing through said loops, acting to interlock the head of the keg with said body.

80 5. In metal kegs, including in combination with the body of the keg, a series of apertures arranged circumferentially of said body adjacent an end thereof, a head for the keg having a portion extended into said end, forming a flange whereby to grip the keg in handling, said portion having a series of outwardly extended loops formed therein and adapted to register with and project through said apertures, and an annular band passing through said loops, acting to interlock the head of the keg with said body.

85 6. In metal kegs, including in combination with the body of the keg, a series of apertures arranged circumferentially of said body adjacent an end thereof, a head for the keg having an outwardly rolled edge whereby the head is adapted to be seated on an end of said body, and a portion extended into said end, forming a flange whereby to grip the keg in handling, said portion having a series of outwardly extended loops formed therein and adapted to register with and project through said apertures, and an annular band passing through said loops, acting to interlock the head of the keg with said body.

90 7. In metal kegs, including in combination with the body of the keg, a series of apertures arranged circumferentially of said body adjacent an end thereof, an external, circumferentially arranged groove connecting said apertures, a head for the keg having a portion extended into said end, said portion having a series of outwardly extended loops formed therein and adapted to

register with and project through said apertures, and a binder adapted to be extended around the body of the keg in said groove and through said loops, and adapted to have 5 its ends brought together and united one with the other to draw the binder taught in the groove whereby to interlock the head of the keg with said body.

8. In metal kegs, including in combination 10 with the body thereof, a plurality of channels extended parallel one with another longitudinally of said body, intermediate bands coacting with said channels to maintain the cylindrical shape of said body, a 15 series of apertures arranged circumferentially of said body adjacent an end thereof, a head for the keg seated in said end over the ends of said channels, having a flange portion extended into said end and 20 having a series of loops formed therein adapted to register with and to be pressed outwardly through said apertures, and an annular band passing through said loops, acting to interlock the head of the keg with 25 said body.

9. In metal kegs, the combination comprising a flat piece of sheet metal having opposite edges thereof shaped to form a joint one edge with the other as the sheet 30 is brought to a cylindrical shape to form the body of the keg, a plurality of longitudinal channels formed in said metal parallel with said edges, said joint coming in one of said channels below the periphery of said body, 35 intermediate bands coacting with said channels to maintain the cylindrical shape of said body, a series of apertures arranged

circumferentially of said body adjacent an end thereof, a head for the keg seated in said end over the ends of said channels, having a flange portion extended into said end and having a series of loops formed therein adapted to register with and to be pressed outwardly through said apertures. 40

10. In metal kegs, the combination comprising a rectangular-shaped flat piece of sheet metal having opposite edges thereof shaped to form a joint one edge with the other as the sheet is brought to a cylindrical shape to form the body of the keg, the other 45 opposite edges having a series of apertures and a groove connecting one aperture with another formed therein arranged parallel with the edges, a series of channels formed in said metal extended parallel with said joint; a circumferential band adapted to fit an intermediate position on said body and having a series of lugs arranged thereon adapted to interlock the band with said channels; pieces of metal shaped to form the heads of the keg and having a series of loops formed integrally therewith and adapted as the heads are assembled on the keg to be projected through said apertures, and a wire adapted to be extended in each 50 of said grooves through said loops, and to have its ends joined together whereby to interlock the heads with the body of the keg, all of said parts being in knocked-down form and adapted to be readily assembled 55 and disassembled one with another. 60

In testimony whereof, I affix my signature.

RALPH E. BLACKFORD.
